UNITED STATES PATENT OFFICE.

JOSIAH B. GATHRIGHT, OF LOUISVILLE, KENTUCKY.

GIRTHING MEANS FOR RIDING-SADDLES.

1,145,477.

Specification of Letters Patent.

Patented July 6, 1915.

Application filed April 5, 1910. Serial No. 553,525.

To all whom it may concern:

Be it known that I, JOSIAH B. GATHRIGHT, a citizen of the United States, residing at Louisville, in the county of Jefferson and State of Kentucky, have invented new and useful Improvements in Girthing Means for Riding-Saddles, of which the following is a specification.

This invention relates to girthing means for saddles, and has for its most important purpose the provision of a girthing means of construction such that its fastening elements will automatically interengage when one is moved into proximity to the other. thereby overcoming the need for the use of 10 buckles and the like, and supplying a girthing means which may be most quickly and securely fastened in the darkness as well as in the light and hence will answer the requirements of cavalrymen, cowboys 20 and others who have felt a need for a girthing means of such nature. This purpose, and others which will hereinafter appear, are fully secured from the constructions illustrated in the accompanying drawings, 25 which exemplify what is at present regarded to be the best embodiments of the invention, but to the details of which the invention, in its broader aspects, is not restricted, as changes may be made in the 30 details without departing from the spirit of the invention or the scope of the subjoined claims.

In said drawings: Figure 1 is a side view of a "double-rigged" saddle embodying my invention, showing the girth secured. Fig. 2 is a similar view of a saddle having a single-ring girthing embodying my invention. Fig. 3 is a detail edge view of the fastening 40 members and contiguous parts, prior to adjustment of the latter into fastening relation with each other. Fig. 4 is a similar view of the same parts secured together. Fig. 5 is a detail representation of a modified form of one of the fastening members. Fig. 6 is a detail representation of the ring from which a member of the fastening means is suspended. Fig. 7 is a detail representation, in side elevation, of one of the 50 fastening elements, and Fig. 8 is a like view of the other fastening element.

The same characters of reference designate the same parts in the several views.

A, in both Figs. 1 and 2, designates a riding saddle, which may be of any suitable construction. In the form shown in Fig. 1,

the saddle is "double rigged", being shown as provided with straps 1, 2 and 3 arranged as in the usual swing for such girthing. In the form shown in Fig. 2, the straps designated 1^a and 2^a, are arranged as is usual in "single rig" girthing. In the first form the rigs are provided with a pair of rings, B, which are supported from the saddle by the straps, and in the second form the rig 60 has a single ring. As these rings are of identical construction, whether used in the single rigged saddle or double rigged saddle, they are designated throughout by the same reference character, B. The fastening 65 means also are or may be identical whether used in a single rig saddle or double rig saddle, the only essential difference being that in the double rigged saddle a pair of fastening means are employed.

The ring B, in the herein exemplified forms of the invention, provides an open support for the upper one of two complementary elements C and C' and also serves as a support for and to change the direction 80 of a pull member C², said pull member extending through the ring and having its lower end operatively connected with the lower fastening element C' and its free end arranged in position where it may be 85 grasped and moved, to move the pull member through said ring and thereby raise the lower fastening element C' relatively to the upper fastening element C. Said ring is preferably provided at its lower end with 90 a cross bar 5 which is of less diameter than the adjacent parts of the ring, to form guiding elements for the pull member C². The pull member preferably is a strap, as shown. The upper fastening element C 95 preferably has its upper end formed or provided with a loop or hook 7 by which it is suspended from and pivotally attached to the bar 5 of the ring B. The other element, C', is suitably connected to the girth D and 100 is moved toward and from the element C in the operation of fastening and unfastening the girth. The two elements C and C' are relatively so formed that when one is brought into juxtaposition with the other, by pulling the strap C², a holding engagement of one with the other will be conveniently effected. For this purpose, the element C is shown as being provided with

105 a hook 8 which forms an open bearing into which a bar 9 of the element C' seats itself when the strap C² has been pulled to bring 110

the bar 9 into proper position therefor. This bar 9 is preferably ovoidal in cross-section to best adapt it to travel past the hook 8, and to give it maximum strength 5 and reduce the extent to which the hook 8 must project from the body of the element C as compared with the circular or angular bar. The element C' is also provided with two other bars 10 and 11, spaced apart. The 10 girth D is secured to the bar 11 preferably by a loop d, and the pull strap C² is suitably secured at one end to the intermediate bar 10, and extends thence upward rearward of the bar 9 and of the element C, thence 15 over the top of the latter, between the guiding shoulders 6, 6 of the ring B and to the front of the element C.

As shown in Fig. 2, the pull strap may be secured directly to the girth instead of 20 directly thereto, in which case it extends from the girth upward in front of the bar 10 and behind the bar 9 and to and over the top of the element C from the rear as before explained. Whether the pull strap is connected directly to the element C' or to the girth D it has connection with said element C' such that a downward pull upon the free 25 end of the strap C² will lift and accurately guide the element C' until the bar 9 has passed over the hook. In this movement of the pull strap over the swiveled member C, the lower end of the latter is pressed toward the horse with its hook in the path of the bar 9 and the passing of this bar over the 30 point of said hook is indicated by a distinct "click". When this indication has been given the strap may be released, but the hand should be held sufficiently close to prevent outward swinging of the hook away 35 from the bar before the latter has been seated therein. This pull upon the strap C² after passing its fore end through ring B, and holding of the hand near the animal is all that is necessary to effect the fastening 40 of the girth, and obviously it may be accomplished in an instant and without requiring the user to see the parts, inasmuch as the swinging element C is held against lateral displacement and the pull strap is 45 guided in its proper place of operation by the shoulders 6 already referred to. In order to unfasten the girth, a downward pull is given the strap C² to lift the bar 9 above the point of the hook 8. When this 50 pull is relaxed, the reaction of the girth and strap C² causes the element C' to swing outward and withdraw the hook 8 from the path of downward movement of the bar 9 so as to permit the latter to pass by. During 55 this time, the hand is given a slight outward movement in order that it may not interfere with the described outward swinging movement of the element C.

As shown in Figs. 1, 3, 4 and 8, the element C may be formed or provided with a

depending loop 15 into which the end of the pull strap C² may be tucked when the girth is fastened; or, as shown in Fig. 2, a loop 15^a for the end of the pull strap may be attached to the body of the girth D. 70 These loops, however, are not essential to a secure fastening of the girth and when they are integral with or attached to the element C the strap may be pulled and the girth released without withdrawing the 75 strap from the loop.

As shown in Fig. 5, the member (designated C^a) corresponding to the element C already described, may be provided with a plurality of hooks (designated 8^a) instead 80 of a single hook (8) for purposes of adjustment. When the conditions are such as to not require frequent adjustment of the length of the girth means, the single-hook form is preferable because of its comparative simplicity. It is not essential to my invention that the described fastening elements be arranged at each side, as any suitable fastening means may be used on the off side and occasional adjustment made 90 on that side.

Having thus described the invention what I believe to be new and desire to secure by Letters Patent, is:—

1. In a girth means for a riding saddle, the combination with a saddle rig and a girth, of upper and lower complementary fastening elements, the former of which is suspended from the rig and the other has connection with the girth, said fastening elements being arranged to be movable relatively to each other, and a pull member arranged to raise the lower fastening element into fastening position, the said pull member extending upward from the lower fastening element and the saddle rig having a device over which the pull member moves and which changes the direction of the pull member, one of said fastening elements having a seat and the other having a part arranged to be held by said seat when the lower fastening element has been brought into fastening relation with the upper fastening element.

2. In a girth means for a riding saddle, the combination with a saddle rig and a girth, said saddle rig having an open support at one end, of a fastening element pivotally suspended from said open support, a second fastening element having connection with the girth, and a pull member extending through said support and arranged to raise the second fastening element into fastening relation with the other fastening element, one of said fastening elements having an open seat and the other having a part arranged to be held by said seat when the elements have been brought into fastening relation by force applied to the pull member.

3. In a girthing means for a riding saddle, a girth, an upper fastening element arranged to be pivotally suspended from the saddle, a lower fastening element having connection with the girth, and a pull member arranged to raise the lower fastening element into fastening relation with the upper fastening element, said pull member being disposed at the rear of the upper fastening element and having its free end extending to the front thereof, one of said fastening elements having an open rearwardly extending seat and the other of said fastening elements having a part which engages said seat when the fastening elements have been brought into fastening relation by force applied to the pull member. 70
4. In a girthing means for a riding saddle, the combination with a saddle rig and a girth, said saddle rig having an open support, of a fastening element suspended from the open support and having a rearwardly projecting hook, a second fastening element having connection with the girth and provided with a member adapted to seat in said hook, and a pull member arranged to raise the second fastening element into operative relation with the other fastening element and extending rearward of the latter element and through said open support to the front. 75
5. A girthing means for saddles, comprising a pair of fastening elements one of which has a hook and the other a bar to be received by said hook, an open support upon which one of said elements is swiveled, a pull member extending through said support and having connection with the other of said elements and arranged to move the latter, and a girth having connection with the last named fastening element. 80
6. A girthing means for saddles, comprising upper and lower complementary fastening elements, the upper element having means whereby it is pivotally supported from the saddle and the lower element having connection with the girth, one of said elements having a bar which is ovoidal in cross section and the other having a hook to receive said bar, and means for raising the lower element into fastening relation with the upper element, comprising a pull member having connection with said lower element and engaged intermediate of its length by a support over which it travels and which changes its direction. 85
7. A girthing means for saddles, provided with a ring having a bar of less diameter than contiguous portions of the ring, forming shoulders, a fastening element pivotally supported by said bar and held against lateral movement by said shoulders, a second fastening element, a girth connected with the latter element, and a pull member extending through said ring and be- 90
- tween said shoulders, said pull member being arranged to raise the second fastening element into fastening relation with the other fastening element and said fastening elements having complementary interengaging parts one of which forms a seat for the other. 95
8. A girthing means for saddles, comprising an open support having means by which it is suspended from the saddle, an upper fastening element pivotally suspended from said support, a lower fastening element having connection with the girth, and a pull member having connection with the lower fastening element and extending through the support, said fastening elements having members which engage each other when they are brought into fastening relation by force applied to the pull member and thereby hold the fastening elements together, one of said elements being provided with a loop for receiving the free end of the pull member when the fastening elements have been engaged with each other. 100
9. In a girthing means for a riding saddle, an open support arranged to be suspended from the saddle, a girth, a fastening element suspended from said support, a second fastening element having connection with the girth, said fastening elements being respectively provided with a rearwardly extending open hook and a bar to seat in said hook when they have been brought into fastening relation with each other, and means for raising the second fastening elements into fastening relation with the other fastening element, said means comprising a pull member arranged rearward of the first-mentioned fastening element and extending to the front through said open support, the open support having means for guiding the pull member and for holding the first-mentioned element against lateral movement. 105
10. A girthing means for saddles, comprising a rig having a ring, a fastening element pivotally suspended from said ring and provided with an open seat, a second fastening element having connection with the girth and provided with a member to engage said seat, a pull member having connection with the second fastening element and extending thence upward through the ring and downward from the ring, the pull member being movable through the ring and said ring having shoulders which confine the first-mentioned fastening element and pull member against lateral movement, and means for holding the free end of the pull member when the fastening elements are engaged with each other. 110
11. The combination with a saddle and a girth, a ring connected to the saddle, a fastening element pivotally suspended from the ring and provided with a hook and a loop, 115
- 120
- 125
- 130

a second fastening element, connected to the girth and provided with a bar to engage the hook of the first mentioned fastening element, and a pull member arranged to lift the second fastening element and engage the bar of the latter with the hook of said first-mentioned fastening element, said pull member extending through the ring from the rear and having its forward free end ar-

ranged to be engaged by the loop of the first- 10 mentioned fastening element.

In testimony whereof I have hereunto set my hand in presence of two subscribing witnesses.

JOSIAH B. GATHRIGHT.
